ABSTRACT: A connector device having substantially parallel prongs at each end. The prongs have exposed free ends for engaging the loop ends of a pair of straps of adjacent letter panels of an aerial display banner. The connector device is also provided with means for holding a stiffening rod substantially parallel to the prongs and between the straps.

These connector devices are adapted to be used in sets, each set being received on and spaced longitudinally of a single rod and connected to the plurality of straps between a pair of adjacent letter panels. Thus, each pair of adjacent letter panels are connected by a set of the connector devices and a single stiffening rod.

CONNECTOR DEVICE FOR AERIAL BANNER DISPLAY

BACKGROUND OF THE INVENTION

This invention relates to a connector device, and more particularly to a connector device particularly adapted for connecting letter panels in an aerial display banner.

Aerial display banners are made up of a plurality of letter panels in series, each panel being detachably connected to an adjacent letter panel, so that the letter panels spell a desired word or words for aerial display.

Typically, each panel is formed of a plurality of vertically spaced straps, preferably made of nylon, to which are secured a large letter of the alphabet made of fabric, plastic or any other convenient material. The attachment of the letter to the straps fixes the spacing of the straps. Various types of connector devices have been employed for connecting the opposed adjacent ends of the straps of adjacent panels to form the entire aerial streamer or banner. However, since these letter panels are repeatedly connected, disconnected and reconnected, to spell different words for aerial display, there is a need for a connector which will not only securely hold the panels together in flight, but which may be disconnected and connected with a minimum of time and effort. The connector devices now in use require considerable time and skill in connecting the strap panels together.

The need for an improved connector device is readily apparent in considering the assembly of immense panels to spell a 10-letter word, when each letter panel includes approximately seven straps. Thus, for a 10-letter word, the banner would require approximately 77 connector devices, the trailing set of connector devices being required to connect the last letter panel to a stiffening rod.

SUMMARY OF THE INVENTION

It is therefore an object of this invention to provide a connector device, particularly adapted for the connection of letter panels in an aerial display banner, in which the connectors can be rapidly connected and disconnected with a minimum of effort. Moreover, the connector device made in accordance with this invention is formed of a single spring wire of economical construction.

The single spring wire of this connector device is bent or looped upon itself to form a clamplike member having its end portions forming substantially parallel prongs, with portions of the wire biased against the prongs to form clamping means. The middle portion of the wire is coiled about an axis substantially parallel to the prongs and having uniform coils to receive and grip a stiffening rod.

In assembling the letter panels of an aerial display banner, in which it will be assumed that each letter panel is formed of seven-spaced straps having looped ends, the stiffening rod is inserted longitudinally through the coiled holding means of seven connector devices so that the spacing of the connector devices is equal to the spacing of the straps. The adjacent looped strap ends of a pair of adjacent letter panels are then slipped over the free ends of the prongs until the prongs extend completely through the looped ends. The looped ends are held in place on the prongs by the clamping portions of the wires. After the desired number of letter panels are connected to each other and the banner is connected to the airplane, the banner is ready for aerial display. As the plane pulls the banner, great tension is exerted upon the panel straps and the connector devices. As adjacent straps pull in opposite directions upon the connector devices, the prongs tend to pull away from each other. However, the tension exerted through the single piece of wire from one prong to the other is transmitted through the coils of the holding member tending to contract the coils tighter about the stiffening rod. The stiffening rods are provided to maintain the letter panels in a substantially upright, flat position without folding, turning or twisting which would destroy the visibility of the letters to the ground observer.

BRIEF DESCRIPTION OF THE DRAWINGS

FIG. 1 is a side elevational view of two sets of the connector devices made in accordance with this invention, connecting a letter panel, incorporating only three straps, for simplicity of illustration, to adjacent letter panels, shown fragmentarily;

FIG. 2 is an enlarged front elevational view of the connector device;

FIG. 3 is a right-end elevation of the connector device disclosed in FIG. 2; and

FIG. 4 is an enlarged section taken along the line 4-4 of FIG. 1.

DESCRIPTION OF THE PREFERRED EMBODIMENT

Referring now to the drawings in more detail, FIG. 1 discloses a portion of an aerial banner 10, including a letter panel 11, shown fragmentarily, a letter panel 12, and a letter panel 13, shown fragmentarily, all connected in series. Although letter panels in actual use will incorporate normally six to eight straps, nevertheless for the purposes of illustration, the letter panels 11, 12 and 13 are disclosed as having only three straps each. Letter panel 11 includes an upper strap 15, middle strap 16 and lower strap 17; letter panel 12 includes upper strap 18, middle strap 19 and lower strap 20; and letter panel 13 includes upper strap 21, middle strap 22 and lower strap 23. Each of these straps 15-23 is preferably made of nylon, or any other material of the desired strength and inertness to atmospheric conditions. Furthermore, each of these straps 15-23 has its opposite ends terminating in loops 25 formed, as shown in the drawings, by turning each end upon itself and securing by a line of stitching 26, or by any other convenient means.

As illustrated by the letter panel 12, a large capital letter, such as the letter U (28), is secured to the three panel straps 18, 19 and 20, by any convenient means, such as adhesive, stitching, or otherwise.

As disclosed in FIG. 1, each of the letter panels 11, 12 and 13 are connected serially to each other by a plurality of sets of connector devices 30 and elongated rigid stiffening rods 32.

Each connector device or body member 30 is preferably made of a single piece of wire bent into the shape disclosed in the drawings. The end portions of the wire connector device 30 form prongs 33 and 34 which are disposed parallel to each other. Also as disclosed in the drawings, and in the preferred form of the invention, the prongs 33 and 34 have free ends which point in opposite directions. The bases or closed ends of the prongs 33 and 34 are bent at approximately right angles to form link portions 35 and 36, respectively, which extend transversely to the opposite ends, respectively, of the body member 30. The link portions 35 and 36, respectively, then are turned approximately 90° to form clamp portions 37 and 38, adjacent to and biased against the respective prongs 34 and 33.

The ends of the clamp portions opposite from the link portions 35 and 36 are again turned approximately 90° and continue inward toward the center of the body member in the form of arms 39 and 40 which terminate in the opposite ends of a coiled holding means or rod holder 41. The coiled rod holder 41 has a uniform diameter and an axis which is substantially parallel to the prongs 33 and 34. The diameter of the rod holder 41 approximates the diameter of the rod 32 so that rod 32 may be slip-fit axially through the coiled rod holder 41. The rod 32 is held in position by the rod holder 41 and adapted to be bound by the contraction of the coils in the rod holder 41 when tension is applied in opposite directions upon the prongs 33 and 34 away from the rod holder 41.

It will be noted that the wire of the connector body member 30 is bent so that the clamp members 37 and 38 are biased by the resilience of the wire toward engagement with the respective prongs 34 and 33. Also the coils 41 are wound in such a direction that tension exerted upon their opposite ends through arms 39 and 40, clamp members 37 and 38, link por-

tions 35 and 36 by the outward strain of the loop portions of the straps upon the prongs 33 and 34 will tend to bind the coils tighter about the stiffening rod 32.

In the operation of the invention, a number of connector devices 30 are selected equal to the number of letter panels 11, 12 or 13 to be used, multiplied by the number of straps in each panel, plus an extra set of connector devices for connecting the forward letter panel to the draft harness, not shown, which is connected to the plane. The letter panels are selected and arranged in the order in which they will be assembled to spell a particular word, so that the looped ends of adjacent straps are generally aligned.

To facilitate the connection of the connector devices 30 to the straps, the rod 32 is first inserted through the rod holders 41 of the desired number of connector devices 30, while there is an absence of tension upon the prongs 33 and 34. In this manner, the body members 30 may be assembled and longitudinally spaced at the desired locations, that is, to have the same spacing as the straps, prior to connection of the looped ends 25 to the respective prongs 33 and 34.

If the letter panel 11 is the first panel and the letter panel 12 is the second panel, then the adjacent ends of the upper straps 15 and 18 are first joined by a connector device 30. The prong 33 is inserted through the loop 25 of the strap 15, and the prong 34 is inserted from the opposite direction through the looped end 25 of the strap 18. The adjacent clamp members 38 and 37 are separated, either manually, or by the exertion of the loop 25 moving over the prong, until the prong 33 extends completely through the looped end 25 and the strap 15. In this position, the clamp member 38 firmly engages and squeezes the portion of the looped end 25 between the prong 33 and the clamp member 38. In a similar manner, the prong 34 is inserted through the looped end 25 of strap 18 and clamped into position by the clamp member 37.

The remaining connector devices 30 on the rod 32 are subsequently connected to the adjacent looped ends 25 of strap pairs 16-19 and 17-20, in the same manner as the upper strap pairs 15-18.

In order to afford an even stronger connection and a better clamping action, the looped end 25 of each strap such as strap 16, may be passed on the inside of and around the clamp member 38, and then slipped over the free end of the prong 33, as shown in FIG. 4. In this manner, the tension in the strap 16 will cause the portion of the strap between the looped end 25 and the rest of the strap 16 to bear against and urge the clamp member 38 more tightly against the looped end 25, thus providing a self-clamping or self-locking feature when tension is applied to the straps as they are drawn through the air.

Moreover, the exertion of the wrapped portion of each looped member 25 about the clamp members 38 and 37 exerts tension through the arms 39 and 40 to contract the coils in the rod holder 41.

After all of the straps 18, 19 and 20 have been connected through the connector devices 30 to the corresponding straps 15, 16 and 17 of the panel 11, then the next set of connector devices 30 are fitted in spaced relation longitudinally upon another rod 32. The next set of connector devices 30 are then connected to the looped ends 25 of the respective straps 18,

19 and 20 of panel 12, and straps 21, 22 and 23 of panel 13. This procedure is continued until all of the letter panels are connected serially to each other.

With the connected panels lying on the ground in the form of a completed banner, and properly connected to the draft harness attached to the plane, the banner 10 is ready for flight.

After the banner 10 is airborne, the tension exerted through the aligned straps of the respective panels is transmitted through the intermediate connector devices 30 to urge the devices into tighter clamping engagement against the straps and also the respective coil holders 41 more tightly about the stiffening rods 32.

After the plane has landed, and tension is relaxed through the straps and connector devices 30, the looped ends 25 may be removed from the free ends of their respective prongs 33 and 34 to rapidly disconnect the connector devices 30, so that they may be stored for their next use. Although the holders 41 may be easily slipped off their respective rods 32, since the tension in the coiled holder 41 is relaxed, if desired, nevertheless since the rods 32 are normally always used with the connector devices 30, they may remain assembled in their respective sets for interconnecting the next combination of adjacent panels.

What is claimed is:

1. A connector device comprising:
 a. a body member having opposite end portions,
 b. said end portions comprising substantially parallel prongs, each prong having one free end for receiving the looped end of a straplike member, so that said body member connects the looped ends of a pair of straplike members,
 c. holding means on said body member adapted to receive a rodlike member substantially parallel to said prongs,
 d. said holding means being between said opposite end portions so that the forces exerted by tension in said straplike members on said prongs will be in opposite directions from said holding means.

2. The invention according to claim 1 in which said body member comprises clamp means biased toward engagement with each of said prongs to hold the looped end of a straplike member on each prong.

3. The invention according to claim 2 in which said prongs and said clamp means are formed of a single piece of spring wire, in which the free ends of said prongs are the ends of the wire and the wire is looped from end to end of said body member to form said clamp means.

4. The invention according to claim 3 in which said wire is coiled in substantially the middle of said body member to form said holding means, so that when tension is applied in opposite end-to-end directions of said body member upon said prongs, the coils of said holding means tend to contract.

5. The invention according to claim 1 comprising a plurality of said body members and an elongated rod, said rod extending through the holding means of each of said body members so that said body members are spaced longitudinally on said rod for connecting the adjacent looped ends of spaced pairs of aligned straplike members.
